UNITED STATES PATENT OFFICE.

FRANK V. BURTON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ATTACHMENT-PLUG RECEPTACLE.

1,169,613.

Specification of Letters Patent. Patented Jan. 25, 1916.

Application filed June 23, 1915. Serial No. 35,924.

To all whom it may concern:

Be it known that I, FRANK V. BURTON, a citizen of the United States of America, and residing at Bridgeport, in the county of 5 Fairfield and State of Connecticut, have invented a certain new and Improved Attachment-Plug Receptacle, of which the following is a specification.

My invention relates to attachment plug 10 receptacles and particularly to a device of the flush receptacle type, the object of my invention being to provide a receptacle having its receiving contacts so arranged as to coöperate with the jack blades of plugs of 15 different constructions.

In the accompanying drawings, Figure 1 is a plan of a receptacle in which my invention is embodied in one form; Fig. 2 is a similar view with the cover plate and portion 20 of the insulating body of the receptacle removed; Fig. 3 is an inverted plan of the body of the receptacle; Fig. 4 is a longitudinal section through the same; Figs. 5 and 6 are side elevations of attachment 25 plugs of different constructions with which the present receptacle is adapted to coöperate; Figs. 7 and 8 are side elevations of receiving contacts carried by the receptacle; and Fig. 9 is a broken elevation of portion 30 of the base.

Attachment plugs of the types shown in Figs. 5 and 6 are now employed to a large extent as connections for use with various types of electrically driven appliances. In 35 the plug 10, shown in Fig. 5, the jacks 11, in the form of blades, are arranged in line with each other and provided with notches 12 on their edges to engage with bosses on the receiving contacts of a coöperating receptacle. In the plug 13, shown in Fig. 6, the jack blades 14 are arranged in parallel 40 and have cups 15 formed in their faces to engage coöperating bosses on the receiving contacts of a suitable receptacle. Heretofore it has been necessary to use receptacles 45 of distinct construction for each type of attachment plug, since it is obviously impossible to insert the parallel jack blades 14 in the slots of a receptacle adapted to receive 50 alined jack blades, such as 11, carried by the plug 10. The present construction provides a receptacle in which the contacts of the receptacle are adapted to coöperate with either type of plug. Since the receptacles 55 are commonly sold independent of the plugs

and are permanently installed in the wall of a house, shop, or the like, it is obviously a decided advantage to have its contacts of such construction that they will receive the jacks of either type of plug. This is more 60 particularly so in view of the fact that current using devices such as electric flat-irons, fans, toilet appliances, etc., are commonly supplied by manufacturers with cord and plug assembled, some using one type of 65 plug and others using the other type, while the receptacles are commonly supplied by an independent manufacturer. The provision of a receptacle adapted to receive one or the other type of plug is of great value 70 to the consumer since it affords a device which is therefore to a certain extent universal in its utility.

As here shown, the present device comprises an insulating base 16, on the depressed shoulders 17 at the diagonally opposite corners of which are mounted terminal plates 18, carrying binding screws 19 for the line wires. The securing screws 20 for the terminal plates connect the latter to straps 21 75 let into the lower face of the base 16, through which the current is conducted by screws 22 to the plates 23 arranged in the bottom of a circular well 24 formed in the upper face of the base 16. Jack-receiving 80 terminals 25, 26, 27 and 28 are secured to plates 23 in such manner that they form coöperating pairs of terminals for the blades of attachment plugs of the different types 10 and 13, illustrated in Figs. 5 and 6. 90 Thus receiving terminals 25 and 26 are alined or, in trade parlance, arranged in tandem to coöperate with the blades 11 of the plug 10, while the terminals 27 and 28 are arranged in parallel to coöperate with 95 the blades 14 of the plug 13.

To inclose the several receiving terminals in separate chambers, I provide an insulating block 29 fitting within the well 24 and secured in assembled position therein by 100 means of a securing screw 30. This block is pierced at 31, 32, 33 and 34 in register with the receiving terminals 25-28 to permit the entry of the latter into the contact chambers formed by the piercing of the 105 block. These chambers opening also to the upper face of the block permit the entry therein of the jacks of the attachment plugs which, when inserted, engage the receiving terminals 25, 26, or 27, 28, depending upon 110

the type of plug employed. The receiving terminals may be of any suitable shape, but they are here shown as straps, the upper ends of which are angled to afford a spring 5 connection with the plug jacks, thus insuring a good electrical contact therewith and at the same time frictionally engaging the same against accidental withdrawal. The spring ends of the terminals 27 and 28 are 10 provided with bosses 35 adapted to coöperate with the recesses 15 in the faces of the jacks 14 of the plug 13, thus reinforcing the frictional engagement of the receiving terminals by a readily freed mechanical engagement.

The cover plate 36 for the receptacle overlies the base 16 and is provided with a central aperture 37 within which fits the upper end of the block 29 so that the face of the 20 latter is substantially flush with the face plate. This block may also be provided with a peripheral flange 38 which overlies the upper edge of the base 16 and by its engagement therewith insures the maintenance 25 of the face of the block substantially flush with the outer surface of the face plate 36.

The usual securing ears 39 are carried by the base 16 and afford means for securing the face plate thereto by means of screws 40.

30 The particular construction of the receiving contacts 25-28 may be varied in many ways as may also the particular arrangement of the slots 31-34 of the block 29, and I do not limit the invention to the particular construction shown in this respect or in other respects which do not depart from what I claim as my invention. Obviously 35 also the invention may be embodied in a fitting which comprises an attachment plug 40 receptacle merely as one element of a group, such for instance as a heater control fitting in which an attachment plug receptacle is combined with a switch and signal light on a common base.

45 I claim as my invention:—

1. An attachment plug receptacle having receiving terminal means having contacts

suitably arranged to engage either substantially parallel or substantially tandem jack blades on a coöperating plug.

2. An attachment plug receptacle having a pair of base plates and receiving terminal means thereon having contacts suitably arranged to engage either substantially parallel or substantially tandem jack blades on 55 a coöperating plug.

3. An attachment plug receptacle having an insulating base, upwardly-projecting terminal means having contacts suitably arranged to engage either substantially parallel or substantially tandem jack blades on a coöperating plug, and an independent cover block of insulation inclosing said terminal means and recessed to form insulated contact chambers for terminals of different 65 polarity.

4. An attachment plug receptacle having an insulating base, upwardly-projecting terminal means having contacts suitably arranged to engage either substantially parallel or substantially tandem jack blades on 70 a coöperating plug, and an independent cover block of insulation inclosing said terminal means and pierced to form an independent contact chamber for each receiving 75 terminal.

5. An attachment plug receptacle having an insulating base, a pair of conductor straps mounted on the lower face of said base and a pair of terminal means on the upper face 80 of said base respectively electrically connected to said conductor straps, each of said terminal means having contacts suitably arranged to receive an attachment plug having its blades arranged either substantially 85 in parallel or substantially in tandem.

In testimony whereof I have signed my name to this specification, in the presence of two subscribing witnesses.

FRANK V. BURTON.
